UNITED STATES PATENT OFFICE.

LOUIS HENRY WILLIAMS, OF ST. JOSEPH, MISSOURI.

CLOTH-CUTTER.

1,122,050.

Specification of Letters Patent. Patented Dec. 22, 1914.

Application filed April 4, 1914. Serial No. 829,501.

To all whom it may concern:

Be it known that I, LOUIS H. WILLIAMS, a citizen of the United States, and a resident of St. Joseph, in the county of Buchanan and State of Missouri, have invented 5 a new and Improved Cloth-Cutter, of which the following is a full, clear, and exact description.

The object of my invention is to provide 10 a cloth cutter having a knife normally disposed within a casing which is mounted on a track bar along which it is adapted to move, the track bar having means for holding the cloth to be cut against a corrugated 15 member on a base to which the track bar is articulated.

Additional objects of the invention will 20 appear in the following specification in which the preferred form of my invention is disclosed.

In the drawings similar reference characters refer to similar parts in all the views in which—

Figure 1 is a view showing in perspective 25 a table or counter to which my invention is applied; Fig. 2 is a perspective view of my invention; Fig. 3 is an enlarged sectional fragmentary view showing the means for articulating the track bar with the base; Fig. 4 is a fragmentary view showing in 30 perspective, the means for detachably securing the outer end of the track bar to the base; and Figs. 5 and 6 are enlarged sectional views showing the construction of the 35 casing with the cutter disposed therein.

By referring to the drawings it will be 40 seen that a base 5 is provided, this base, if desired, being recessed in a table or counter 6. In the end of this base there is a recess 8 in which a transverse pin 9 is secured, a bolt 10 having an eye 11 through which the bolt 10 passes. This bolt 10 is also disposed through an opening 12 in the bracket 13. The bracket 13 has vertically 45 disposed flanges 14 spaced apart between which is disposed the end 15 of the track bar 16, there being an orifice 17 in the said end 15 of the track bar, through which is disposed a pin 18 which is secured to the flanges 14. In the base 5 there is a longitudinally disposed slot 19 which extends 50 through the upper surface of the base 5, and in the track bar 16 there is a longitudinally extending slot 20 which extends 55 through the upper and lower surfaces of the track bar, the slot 20 being disposed in alignment with the slot 19 when the track bar 16

is in normal position over the base 5. In order to hold the track bar in normal position, I provide the outer end 21 of the track bar with a pin 22 which is adapted 60 to be disposed in the recess 23 in the track 24 which is secured to the base 5.

Mounted for moving on the track bar 16 there is a casing 25, this casing 25 having inwardly disposed flanges 26 at its sides 65 which are normally disposed in the guide-ways 27 in the sides of the track bar 16, the casing 25 being movable along the track bar and being prevented from becoming displaced by the engagement of the 70 track bar 16 by the flanges 26 at the guide-ways 27. This casing 25 has a vertical slot 28 which is disposed in alinement with the slot 20 in the track bar 16. In this slot 20 there is disposed a lever 29 consisting of 75 the sections 30, this lever 29 being pivoted to the casing at 31. The sections 30 of the casing are secured together by the bolts 32 and 32^a, a knife which may be a safety razor blade 33, being clamped between the 80 sections 30 by means of the said bolts or screws 32 and 32^a. The ends 34 of the sections 30 of the lever 29 are normally disposed beyond the end 35 of the casing 25, so that the bolt 32^a is disposed beyond 85 the said end 35 of the casing, this bolt 32^a serving to engage the end 35 of the casing to limit the upward movement of the end of the lever 29, which carries the knife 33. The other end 29^a of the lever is upwardly 90 disposed and is provided with a finger piece 36 by which the said end 29^a of the lever 29 may be moved toward the casing 25 to carry the end 29^a of the lever 29 down and with it the knife 33, the knife moving 95 through the slot 20 in the track bar 16 to a position within or adjacent to the slot 19 of the base 5. The end 29^a of the lever 29 is normally held away from the casing 25 by a spring 37 which is secured to the end 100 29^a of the said lever adjacent to the finger piece 36, this spring 37 also bearing against the casing 25 at the end 38 of a recess 39 which is made in the top of the casing 25 to receive the said spring 37. 105

As a means for holding the cloth between the base and the track bar 16 when the cloth is to be cut, I provide the base 5 at either side of the slot 19 with corrugated rubber strips 40 and the lower surface of the track 110 bar 16 at either side of the slot 20 is provided with strips of velvet 41.

As shown in Fig. 1 of the drawings, a

hook 42 may be secured to the edge of the table for receiving the pin 22 when the track bar 16 is raised from the table or counter 6 and is moved on its pivots to a 5 position along the edge of the table.

Having thus described my invention I claim as new and desire to secure by Letters Patent:

1. In a cloth cutter, a track bar having a 10 slot, a casing mounted on the track bar and movable therealong, there being a slot in the casing in alinement with the slot in the track bar, a lever in two parts and pivoted with the slot in the casing, a knife dis- 15 posed within the parts of the lever, a bolt for clamping the parts of the lever together with the knife therebetween, the bolt being positioned for engaging the casing to limit the movement of the lever relatively to the 20 casing and resilient means for holding the lever yieldingly with the knife within the casing.

2. In a cloth cutter, a track bar having a slot, a casing movably mounted on the track bar, a member having a slot in the 25 casing in alinement with the slot in the track bar, a lever fulcrumed within the casing, a knife disposed within the casing and secured to one arm of the lever, the other arm of the lever extending upwardly, 30 a spring having one terminal extending upwardly and secured to the last mentioned arm of the lever, and another terminal extending upwardly and bearing against the casing. 35

In testimony whereof I have hereunto signed my name to this specification in the presence of two subscribing witnesses.

LOUIS HENRY WILLIAMS.
